AUTOMATIC WIRING MACHINE

Chester C. Bach and Andrew J. Clark, Downers Grove, Ill., Willard D. Drukker, Worthington, Ohio, Gerald H. Klenke, Batavia, and Elmer N. Lenk, Westchester, Ill., and Heinz F. Runge, Madison, Wis., assignors to Western Electric Company, Incorporated, New York, N.Y., a corporation of New York

Filed Sept. 4, 1959, Ser. No. 838,291

21 Claims. (Cl. 219—79)

This invention relates to an automatic wiring machine and more particularly to a wiring machine comprising a pair of selectively positionable wiring tools, the translation of which through a three dimensional coordinate system to accomplish automatic wiring operations is directed by instrumentalities associated with and controlled from a source of intelligence pulses.

The need for automatically controlled wiring, welding and other similar wire-fabricating machines has initiated the development of several types of automatic wiring devices. These devices and others similar thereto do not, however, include a completely versatile device which may be utilized to perform numerous wire-working operations on stationarily positioned articles in conformity with predetermined specifications. It is extremely desirable in a device of this sort that the relative positions of the several wire-working tools be established and thereafter advanced relative to a selectively positionable work-holding fixture to accomplish the necessary wiring operation. Furthermore, a device of this sort should be adaptable for use with relay-sequencing circuits which can positively and accurately accomplish the simultaneous positioning of two carriages in a three dimensional coordinate system.

A prime object of this invention is to provide a new and improved automatic wiring machine.

An additional object of the invention is the provision of a wiring machine having a pair of carriages that may be selectively positioned within a three dimensional coordinate system and which have secured thereto wire-working tools to accomplish wiring operations on articles in accordance with predetermined specifications.

A further object of this invention resides in an automatic wiring machine having a first carriage which may be advanced in accordance with a predetermined programmed mode of operation and a second carriage which may be secured to the first carriage by a gripping means; thereafter the two carriages may be simultaneously advanced in a horizontal direction.

Another object of the invention resides in an automatic wiring apparatus having both a selectively positionable work-holding fixture and a wire-supply device positioned at opposite extremities of a support frame which houses the three dimensional coordinate system through which a pair of carriages may be selectively translated.

Still another object of this invention resides in an automatic wiring machine having a source of intelligence pulses which selectively condition mechanical and electro-mechanical instrumentalities for operation to accomplish the advance of a pair of carriages from positions in alignment with a wire-feeding device into preconcerted positions at a work-holding fixture whereat wire welding or other wire-fabricating operations may be accomplished.

With these and other objects in view, the present invention contemplates an automatic wiring machine which comprises a pair of carriages having two welding guns secured thereto together with punch tape control facilities for selectively positioning each gun in an "XYZ" left-hand coordinate system. A first gun grasps a stripped end of a wire and is advanced a horizontal distance equal to the spacing between the terminals and in addition

2

thereto an incremental length sufficient to provide for the vertical displacement of the terminal to which the opposite end of the wire is to be secured. At the same time, the gun is being elevated into a position indicative of the vertical spacing of the first terminal to be wired. The other gun seizes the wire which has been stripped and severed at the opposite end and is moved horizontally and vertically into position indicative of the vertical and horizontal spacing of the second terminal to be wired.

10 The two carriages on which the guns are mounted are then joined by means of a towing device and simultaneously moved horizontally to bring the ends of the wires into alignment with the selected terminals. The guns are then moved into a welding position in close proximity to said terminals, and are operated to complete the wiring operation. The terminals to be wired are positioned on terminal boards which are in turn secured within holding brackets mounted for rotation within a frame. The frame is in turn mounted for selective vertical position 20 ment in accordance with information derived from the punch tape. The aforementioned carriages, wiring guns and other apparatus are provided with a program mode of operation from a tape reader which selectively operates an electrical circuit to control the cyclic operation of the machine. The circuit includes a number of coincident and commutator controlled elements for initiating and regulating the movement of the various components of the machine.

Other objects and advantages of the present invention 30 will become apparent from the following detailed description when considered in conjunction with the following drawings wherein:

FIG. 1 is a front elevational view, partially broken away, of an automatic wiring machine embodying the 35 principles of the present invention;

FIGS. 2 and 2A, when arranged as shown in FIG. 3, comprise an enlarged fragmentary front elevational view illustrating a pair of carriages together with a drive means for selectively positioning the carriages with respect to a 40 bank of terminals as shown in phantom outline;

FIG. 4 is an enlarged side elevation, partially in section, taken along the line 4—4 of FIG. 2 and illustrating a right gun carriage, guide rods for the carriage and an "X" and "Y" coordinate positioning means;

FIG. 5 is an enlarged fragmentary side view taken 45 along the line 5—5 of FIG. 2 illustrating a rack and pinion drive means for the right gun carriage and a tow bar gripping means secured to the left gun carriage;

FIG. 6 is an enlarged cross-sectional plan view taken 50 along the line 6—6 of FIG. 2 illustrating base plates of the right and left gun carriages, a detent bar, and the tow bar which is selectively gripped by the left gun carriage during a horizontal translation of the various elements;

FIG. 7 is an enlarged fragmentary side view illustrating the left gun carriage and an associated percussive 55 welding gun which has been horizontally and vertically translated through the "X" and "Y" coordinate system into alignment with a terminal projecting from one of several mounting plates and further illustrating a cam means for controlling the advance of the gun in the "Z" direction;

FIG. 8 is an enlarged fragmentary elevation illustrating a cutter-stripper means wherefrom wire is advanced and thereafter grasped by the percussive welding 60 guns at the outset of a cycle of operation of the automatic welding machine;

FIGS. 9A to 9g are diagrammatic views of the carriages in various positions during a cycle of operation particularly illustrating welding a wire to a pair of terminals;

FIGS. 11 to 37, when arranged as shown in FIG. 10,

illustrate a simplified schematic diagram of an electrical control circuit for the apparatus shown in the other figures;

FIG. 38 is a view in block diagram form illustrating the flow of intelligence and the associated mechanical operations resulting therefrom for the various instrumentalities incorporated in the present embodiment of the automatic welding machine;

FIGS. 39 and 40, when arranged as shown in FIG. 41, depict a chart for a sequence of operations of the various components during a cycle of operation of the automatic wiring machine embodying the principles of the present invention; and

FIG. 42 is a representation of a portion of the punched tape used for controlling the automatic wiring of the machine depicted in the other figures.

Referring to the drawings, and more particularly to FIG. 9g, the function to be performed by the machine will best be understood. A terminal strip 50 which has a plurality of terminals 51 projecting outwardly therefrom is positioned within the automatic wiring machine and upon the completion of a cycle of operation, wire or other similar strand material 52 will selectively interconnect spaced terminals 51 in accordance with predetermined specifications.

FIG. 1 is illustrative of one embodiment of the automatic wiring machine which comprises, among other things, a base 54 which supports a housing or support frame 56. A work-holding fixture, generally designated by the numeral 57, is situated at one extremity of the wiring machine and positioned in spaced relationship to a plurality of guide rods 58 which have a pair of carriages, generally designated by the numerals 59 and 61, movably mounted thereon. At the opposite extremity of the wiring machine is a control panel 62 and a cabinet-like structure, generally designated by the numeral 63, which houses the electrical components that control the overall operation of the machine. A commercially available tape reader 64 which is mounted at the base of the control panel 62 feeds the programmed mode of operation into the various control units of the machine to provide information for a complete cycle of operation. A pair of motors 67 and 68 constitute the drive means for the carriages 59 and 61 and function to advance these carriages in a horizontal direction.

A pulley 69 and a belt 70 impart rotary movement from the motor 67 to a pulley 71 whereby a shaft 72 may be rotated in either a clockwise or counterclockwise direction. Similarly, the motor 68 through a pulley 73, a belt 74 and a pulley 76 transmits rotary motion to a shaft 77.

Referring to FIGS. 2 and 2A, the elements previously disclosed in a general manner will now be more specifically described. The support frame 56 comprises, among other things, a pair of upwardly projecting braces 79 which are secured to the base 54. The guide rods 58 are secured within these braces and the carriages 59 and 61 are mounted on the guide rods between the braces by means of several elongated bushing members 81. FIG. 4 clearly illustrates the relative positions of the guide rods 58 and the associated bushings 81. Reference to FIG. 4 will also reveal that, while two guide rods 58 extend between the braces 79 at the lower extremity of the carriages, only one such guide rod spans the distance between the upper extremity of the braces 79.

The work-holding fixture 57 is secured to the base by means of a bracket 84. Extending upwardly from the base through the uppermost portion of the bracket are a pair of shafts 86 on which is mounted a mounting plate support member 87. A shaft 88 is secured within bushing members (not shown) in the support member 87. This shaft 88 is secured to a mounting plate 89 which has three terminal strips 50 positioned therein. A pinion 91 is secured to the shaft 88 and has rotary motion imparted thereto by means of a rack 75

92 under the control of a piston 94 and a pneumatic cylinder 93. A pair of microswitches 97 and 98 are positioned so as to be engageable with the rack and thereby sense the positioning of the mounting plate. It is through this means that the shaft 88 and consequently the mounting plate and terminal strips 89 and 50 may be rotated through 180° so that terminal strips may be loaded or unloaded while wiring operations are being performed on terminal strips secured to the mounting plate on the opposite side thereof. The piston 101 and cylinder 102 which are secured to the support frame 87 by means of the pin 100 are utilized to raise and lower the entire mounting plate support frame. Motion imparted to the piston 101 by the cylinder 102 is transmitted to the support frame which then moves relative to the bracket 84 on bearing surfaces which engage the shafts 86.

Each of the carriages 59 and 61 are essentially identical and are comprised of four major components. These components may be generally referred to as a carriage base plate, a coarse vertical positioning elevator, a fine vertical positioning elevator and a tool-mounting plate. Each of the carriages has a base plate 103 (FIG. 6) the forward and rearward sections of which form the elongated bushings 81. Referring to FIG. 6, and more particularly to the base plate 103 of the right carriage 61, it will be noted that a rack 104 and tow bar 106 are secured to the underside of the base plate by a plurality of screws 107. A pair of guide rollers 105 insure the uniform advance of the carriages relative to a detent bar 113 which they constantly engage. Additionally, a cylinder 108 is provided which may be rendered effective to actuate a piston 109 to advance a wedge-shaped detent 111 into one of a plurality of indentations 112 formed in the detent bar 113. A shaft 80 to which is secured a cam follower 85 forms one end of the detent bar 113. The cam follower engages a cam 75 mounted on the shaft 77. The opposite extremity of the detent bar 113 is secured to a piston 115 that is controlled by a cylinder 120 (FIG. 2A). A singular V-notched block 114 is also secured to the underside of the right carriage 61 into which a wedge-shaped detent 116 may be advanced by the cylinder 117 when the carriages are positioned at the load station.

FIG. 5, which represents a side view of the base plate 103 of the left gun carriage 59, serves to illustrate a device for selectively gripping the tow bar 106 generally designated by the numeral 121. This gripping device which is secured to the underside of the left carriage base plate comprises a cylinder 122, a piston 123 and associated linkage 124 which function to selectively advance a pair of gripping jaws 126 into engagement with the tow bar 106. FIG. 5 further illustrates the motor 67 that drives the pulleys 69 and 71 through the belt 70. A clutch 127 which is positioned on a drive shaft 129 and rotatably mounted within a support member 130, that is in turn secured to the base 54, functions to control the operation of the motor 67. The shaft 72 to which the pulley 71 is secured has mounted thereon a pinion 131 that cooperates with the rack 104 and serves as the drive means for the horizontal movement to be imparted to the right carriage 61.

Extending upwardly from each of the base plates 103 of the carriages 59 and 61 are three guide shafts 134 (FIG. 6). Mounted for vertical movement on these guide shafts 134 relative to the base plates 103 are a fine positioning elevator 136 and a coarse positioning elevator 137. Referring to FIG. 4, the two elevators 136 and 137 for the right carriage 61 are shown. A pair of support members 141 and 142, which are provided by both of the carriages, are bored to provide bearings for a shaft 143 which can be selectively rotated under the control of a commercially available D.C. motor 144.

The shaft 143 of the right carriage 61 has mounted thereon a commutator 146 and a single stepped cam 147

which has a plurality of lands 148 beveled therein. The left carriage 59, however, has mounted on the shaft 143 not only the cam 147 but also has secured thereto a cam 149 which is similarly formed but displaced 90° from the cam 147 (FIG. 2). A roller 151 rotatably mounted within a roller housing 152 which is in turn threadably secured to the fine elevator 136 engages the cam 147 and results in the upward advance of the elevator when the D.C. motor is rendered effective and imparts rotary movement to the shaft 143. A Microswitch 153 is mounted on the support member 141 and is utilized to sense the rest position of the fine elevator 136.

The coarse elevator member 137 similarly may be advanced in a vertical direction and a Microswitch 155 is utilized to ascertain if the coarse elevator is in an elevated or a rest position. The means for effectuating such vertical advance is provided by the cylinder 156 which is pneumatically controlled from the source 157. The cylinder 156 is secured to the elevator 137 and has projecting from the lower extremity thereof a piston 158, the end of which is threadably secured to the frame 159 of the fine elevator member 136. Also, projecting upwardly from and secured to the frame 159 is a bar 161 which has three inwardly slanting steps 162 formed on the face thereof. A cylinder 163, which is secured to the frame 164 of the coarse elevator 137 for movement therewith, has a piston 166 to which is secured a wedge-shaped member 167 that complements the steps 162 of the bar 161. Concomitant operation of the cylinders 156 and 163 accomplishes the selective positioning of the coarse elevator.

Projecting upwardly from the base 103 of each of the carriages 59 and 61 and secured thereto is a cylindrical member 171 within which an elongated helical spring 172 is positioned and secured at the lower extremity thereof. The uppermost section of the spring has attached thereto a chain 173 which rides over a freely rotatable sprocket wheel 174 which is mounted on a support member 176 that is in turn secured to and projects outwardly from the elongated bushing 81. The opposite end of the chain 173 is secured by means of a pin 177 to a pair of brackets 178 that are mounted on a frame 179 of the coarse elevator 137. The chain, sprocket wheel and spring mechanism accomplish the smooth return of the coarse carriage to an initial position upon retraction of the piston 158 within the cylinder 156.

Referring now to FIG. 7, the final component which comprises the carriages 59 and 61 shall be described. Positioned within a cylindrical portion 180 of the frame 179 is a spring-loaded pusher rod 181 which is normally held in a retracted position against a contracted spring 182 by means of a cam 183 which abuts an L-shaped cam follower 184 within which the rod 181 is threadably secured. The cam follower 184 projects downwardly from and forms a portion of a tool-mounting plate 186 to which is secured a percussive welding gun generally designated by the numeral 185. Forward and rearward extremities of the mounting plate 186 have threadably secured therein opposite ends of a pair of guide rods 187. Upon rotation of the cam 183 about the shaft 188 to which it is secured, the spring 182 expands and results in the advance of the cam follower and consequently the mounting plate 186. Linear forward and rearward advance of the mounting plate relative to the frame 179 is insured by the passage of the guide rod 187 within a pair of bushings 191 and 192 secured to the frame. A pair of switch actuators 194 and 196 which are secured to the underside of the mounting plate 186 are selectively positioned so as to engage a plurality of Microswitches 197, 198, 199, 201 and 202. These Microswitches cooperate with other electrical circuitry to control the rotation of the cam 183.

The forward downwardly projecting portion of the plate 186 also has threadably secured therein a shaft 206. Bushings 207 and 208 through which the shaft 206 passes insure that a wire-positioning member 209 is advanced inwardly during the positioning of the welding gun 185.

in alignment with the terminal which is to have length of wire secured thereto. A bracket 211 which comprises a portion of the wire-positioning member 209 is secured to the base plate 103 on each of the carriages and is consequently precluded from any movement in a vertical direction. During the upward and inward advance of the gun 185, a hook-like positioning sleeve or mandrel 212 positions or dresses the wire beneath the lowermost terminal 51 on the terminal strip 50. An air cylinder 213 is rendered effective during the inward advance of the welding gun and the positioning of the wire in proper alignment beneath the lowermost terminal by the sleeve 212. The actuation of the air cylinder 213 results in the retraction of the sleeve relative to an inverted L-shaped abutting member 216 which is secured by the pins 217 and 218 through the bracket 211 to the bushings 207 and 208, respectively. The retraction of the sleeve 212 by a piston arm 219 which is threadably secured to the lowermost extremity 221 of the sleeve results in the final positioning of the wire 52. The sleeve 212 moves relative to bushing surfaces formed in the bracket 211 on guide rods 223.

A gun 185, which is identical to the percussive welding gun disclosed in the copending application of J. H. Born, Ser. No. 837,107, filed Aug. 31, 1959, now Patent No. 2,984,733, entitled "Device for Welding Wires to Terminals," is secured to the tool-mounting plate 186 for movement therewith and comprises, among other things, a base plate 231 on which are mounted air cylinder 232 and the associated linkage which functions to actuate the jaws 233. Referring to FIG. 4, a terminal-clamping jaw 234 is shown which cooperates with the wire-gripping jaws to accomplish a percussive welding of the wire 52 to a terminal 51. Upon the advance of the welding gun 185 into alignment with the selected terminal 51, a welding potential which has been impressed upon the terminal and the wire-gripping jaws produces an arc as the wire is carried into engagement with the terminal thereby accomplishing positive welding operation.

Referring now to FIGS. 2 and 8, the formation of the U-shaped strands of wire 52 which will join selected terminals 51 will be understood. Wire or other similar strand material 52 which is fed from a supply reel 251 is advanced through a housing 252 between a pair of freely rotatable rollers 253 and 254 mounted on shafts 256 and 257. Thereafter, the wire is advanced to a cutter-stripper apparatus generally designated by the numeral 258 which is identical with the wire feeding preparing device disclosed in Patent No. 2,886,995 issued May 19, 1959, to C. C. Bach and H. F. Runge. The cutter-stripper apparatus 258 comprises, among other things, a pair of left wire-gripping jaws 259 under the control of a pneumatic cylinder 260, a pair of right wire-gripping jaws 261 under the control of a pneumatic cylinder 270 and the cutter-stripper jaws 262. At the outset of a cycle of operation with the wire positioned as shown in FIG. 8, the right gun is advanced to grip the wire thereby rendering instrumentalities effective to open the left wire-gripping jaws 259. Thereafter, the right carriage simultaneously moves horizontally in the "X" direction and vertically in the "Y" direction until a predetermined length of wire 52 has been withdrawn from the supply reel 251 at which time, the right carriage is stopped and the right wire-gripping jaws 261 are rendered effective by the pneumatic cylinder 270 to grip the wire.

An air cylinder 263, a piston rod 264 and a pusher 265 are then rendered effective to advance the lower cutter-stripper jaw upwardly into engagement with the wire. An air cylinder 267 controls the horizontal advance of the cutter-stripper jaws 262 by means of a pair of guide rods 268 and 269 which are slideably mounted within a plurality of bushings 271. The vertical and horizontal movements imparted to the cutter-stripper jaws 262 by the air cylinders 263 and 267 result in the preparation of the wire to be secured to the terminals 51.

The formation of the left leg of the U-shaped wire

results from the actuation of the cams 147 and 149 and the operation of a pusher mechanism generally designated by the numeral 281. The operation of the pusher mechanism 281 is under the control of an air cylinder 232 and associated piston rod 283 which is secured to a pusher detent bar 284 through a bushing member 286. One extremity of the pusher detent bar 284 has a cam follower 287 projecting outwardly therefrom as best illustrated in FIG. 2. An L-shaped guide bracket 288 which is secured to a shaft 289 at the point 291 serves as a buffer during the return of the left gun carriage and further insures the linear advance of the pusher detent bar 284 and the associated cam follower 287 into engagement with the cam 149. A plurality of V-shaped notches 292 formed in the pushing bracket 284 are provided to accomplish the formation of the U-shaped section of wire in accordance with the height of the terminal strip to which the wire is to be secured. A pneumatic cylinder 294 mounted on a bracket 295 has a V-shaped pin 296 projecting downwardly therefrom which complements the notches 292 to positively position the pusher detent bar and maintain the bracket 284 in stationary alignment during the rotation of the cam 149.

The linear horizontal advance of the left gun carriage 59 prior to the actuation of the gripping device 121 which interlocks the carriages 59 and 61 must be insured due to the critical positioning of the guns that is necessary to successfully accomplish the percussive welding of a length of wire to selected terminals. To insure that the motion imparted to the left gun carriage as a result of the rotation of the cam 149 against the cam follower 287 of the pusher mechanism 281 results in an accurate positioning of the carriage 59, a spring loaded catch device generally designated by the numeral 285 is provided. Upon the return of the left gun carriage to a load position, a plate 290 that is secured to the base 103 of the left gun carriage 59 has a cam surface beveled along one extremity thereof engages a hook-like member 297 thereby resulting in a pivoting of the member. When the carriage has been finally positioned the member 297 returns to a former position in engagement with the non-beveled edge of the plate 290. Upon rotation of the cam 149 against the cam follower 287, the hook-like member 297 will be withdrawn against the action of the spring 298. The withdrawal of the member 297 against the spring 298 will insure positive engagement of the cam 149 with the cam follower 287 until such time as the left gun carriage is interlocked with the right gun carriage and advanced in horizontal direction by the coarse and fine horizontal positioning devices. Subsequent to an interlocking of the two carriages and their simultaneous horizontal advance, the spring 298 will result in the return of the member 297 to an original position. The linear advance of the member 297 during the actuation of the cam 149 is insured by a guide rod 299 which passes through a pair of guide blocks 280 projecting downwardly from the underside of the pusher detent bar 284.

Mode of operation

Prior to a detailed analysis of the component functions as directed by the electrical circuitry illustrated in FIGS. 11 to 37, a general description of a cycle of operation will be beneficial particularly when considered in conjunction with FIG. 38 and FIGS. 9A to 9g. This broad description will be based on the assumption that the machine has previously been in operation and numerous welding operations have been performed prior to the initiation of the cycle of operation to be hereinafter described. Initially, the carriages 59 and 61 must be returned to a load position as illustrated in FIG. 9A. The return of the carriages 59 and 61 and their associated welding guns 185 to a load position occurs simultaneously with the commencement of the operation of the tape reader 64 (FIG. 1 and FIG. 38).

Information which is presented to the tape reader in

75 the form of a punched tape (FIG. 42) is thereafter sent to a tape-intelligence distributor 301. The tape-intelligence distributor 301 includes both distributing circuitry and a checking circuit which is utilized to ascertain that 5 the program presented by the punch tape is in conformity with predetermined specifications. Information present in the tape-intelligence distributor is selectively shunted to the storage unit 302 of the "X" coordinate system control, a sequence unit 303 and the storage unit 304 of the 10 "Y," "Z" and welding gun system controls. However, information from the tape-intelligence distributor 301 will not be transferred to the various storage units until the 15 afore-mentioned carriages 59 and 61 have been returned to a load position. The function of the sequence unit 303 is to control the operation of the other control systems by dictating at which portion of a cycle of operation information will be fed from the various storage units to render the circuitry of the "X," "Y," "Z" and other control systems effective.

20 At the commencement of a welding operation, the sequence unit 303 initiates the operation of the wire-preparation unit 306 which in turn results in the advance of a cut and stripped portion of wire 51 into alignment with the carriages 59 and 61. Information from the storage unit 304 under the control of the sequence unit 303 is presented to the "Z" control circuit 307 and results in the actuation of a motor 308 to advance the right welding gun into gripping engagement with the end portion of the wire as shown in FIG. 9b. Thereafter, the storage unit 304 similarly directs information to the control system 309 to render the right gun "Y" fine motor 144 and "Y" coarse air cylinders 156 effective. Simultaneously, information is shunted from the storage unit 302 to an "X" coarse matrix 313 and "X" fine coincidence unit 314 thereby initiating the operation of the "X" coarse motor 67 and "X" fine motor 68 to drive the right carriage 61. This results in both the vertical and horizontal advance of the right gun as shown in FIG. 9c. FIG. 9d is illustrative of the advance of the left welding gun 59 under the control of the "Z" motor 308 which is pulsed for operation upon the completion of the advance of the right gun and the formation of one leg of the wire which is to join selected terminals.

45 Prior to the advance of the left welding gun in the "Z" direction as shown in FIG. 9d, the wire-preparation unit is once again energized from the sequence unit 303 to accomplish the cutting and stripping of the opposite end of the wire which is to be advanced to the terminal strip 50. It should be noted that during the advance of the right and left welding guns at the load and welding positions under the control of the "Z" motor 308, the gun control circuit 321 which is provided with information from the storage unit 304 selectively controls the operation of the gun terminal gripping jaws 234, the gun wire pick up jaws 233 and the gun welding control 316.

50 Subsequent to the gripping of the wire by the left gun the "Y" fine motor 144 and the "Y" coarse air cylinder 156 are once again actuated to accomplish the positioning of the left gun in the "Y" direction. The pusher mechanism 281 (FIG. 2) is rendered effective simultaneously with the "Y" fine motor 311 and "Y" coarse air cylinders 156 thereby forming the other leg of the U-shaped section of wire as shown in FIG. 9e. During the final positioning of the carriages in the "Y" direction, the "Y" fine 55 commutator 146 directs and controls the positioning of the cams 147 (FIG. 2).

60 Instrumentalities within the sequence unit 303 control the operation of the gripping jaws 126 (FIG. 5) which function to attach the left carriage rigidly to the tow bar 106 which is in turn secured to the base plate 103 of the right carriage 61. Once again the sequence unit directs the operation of the "X" coarse and "X" fine control systems to advance the carriages horizontally and position them in alignment with the terminals 51 to be joined by the wire.

The final simultaneous positioning of the right and left carriages in the horizontal direction as controlled by the "X" fine code disc 326 and the cam 75 is followed by the reenergization of the "Z" motor 308 which cooperates with the "Z" location Microswitches 197, 198, 199, 201 and 202 and the cam 183 to advance the guns to the programmed terminal positions. Following the positioning of the guns in alignment with the terminals to be joined by the wire, the welding unit (not shown) is rendered effective to complete a cycle of operation.

Should it be necessary to join terminals on different terminal strips, the sequence unit will accordingly function to actuate an oil-dyne unit 331 thereby operating the cylinder 102 to position the mounting plate at the desired position as indicated by the Microswitches 334 and 336 or the pusher mechanism 281 will be actuated to form the wire in accordance with the vertical displacement of the terminals. After numerous cycles of operation have been completed, the sequence unit may selectively render the mounting plate rotate drive mechanism 93 effective to advance other terminal strips mounted on the opposite side thereof (into a welding position). The position of the mounting plate and the rotation thereof is sensed by the mounting plate Microswitches 97 and 98.

Control means to be hereinafter described selectively render effective the aforementioned oil-dyne unit which controls the operation of the cylinder 102 and the pusher mechanism 281 to accomplish the interconnection of any two terminals projecting outwardly from three terminal strips 50a, 50b and 50c that are in turn secured within the work-holding fixture 57. For example, a terminal on the upper terminal strip 50a which has had one leg of a U-shaped segment of wire 51 secured thereto (FIGS. 2 and 2A) may be interconnected to a terminal on the middle terminal strip 50b or the lower terminal strip 50c or, if so desired, to a terminal on the upper terminal strip 50a itself by the expedient of securing the other leg of the U-shaped wire segment 51 to such other terminal. By the same token, a terminal projecting outwardly from the lower terminal strip 50c may have one leg of a wire segment 51 secured thereto and the other leg secured to a selected terminal on any of the mounting plates 50a, 50b or 50c. Similarly, the terminals on the middle terminal strip 50b may be secured to desired terminals projecting outwardly from the terminal strips 50a, 50b or 50c.

Considering now a cycle of operation during which a terminal on the lower strip 50c will be connected to another terminal on the same strip, the cylinder 102 will have previously been rendered effective to elevate the mounting plate 89 to an initial or uppermost of the three possible positions, that are illustrated in FIGS. 2 and 2A. The mounting plate 89 must be in the uppermost position whenever at least one of the terminals to be connected is on the lower strip 50c and, generally, the program is set so that all operations involving the lower strip 50c are completed before any operations are performed involving only the middle and upper strips 50b and 50a.

After the right gun 185 has been moved upward and to the right so as to withdraw from the supply reel 251 the desired length of wire for the U-shaped segment 51 and form the right leg of the U, the pusher detent bar 284 will be advanced to the right by the cylinder 282 to a position where the first V-shaped notch 292 (that furthest to the right in FIG. 2) aligns with the detent 296. This moves the left carriage 59 and gun 185 to the load position, and occurs during each cycle of operation regardless of the locations of the terminals to be connected.

The alignment of the notch 292 will occur simultaneously with the engagement of a Microswitch 400 by a switch actuator 401 that projects outwardly from one side of the detent bar 284 (outwardly from the plane of the drawing as viewed in FIG. 2). The Microswitch 400 when actuated, functions to preclude further advance of the pusher detent bar 284 by rendering the drive means

therefor ineffective and by advancing the detent 296 into engagement with the first notch 292.

In this cycle of operation (both terminals on the same strip 50c), there is no further movement of the pusher detent bar 284, and the horizontal and vertical movements of the left gun 185 to form the left leg of the U-shaped wire segment 51 are caused exclusively by the cams 149 and 147, respectively. These controls, only, are effective when both terminals to be connected are on the lower strip 50c.

Where the program dictates that a terminal on either of the terminal strips 50b or 50a is to be interconnected with another terminal on the same strip, the detent 296 will again engage the first V-shaped notch 292. However, in this instance, the cylinder 102 will be rendered effective to lower the terminal-strip mounting plate 89 a distance equal to the height of one terminal strip where the middle strip 50b is involved and two terminal strips where the upper strip 50a is involved. When this has been done, the strip 50b or 50a being operated on will have assumed the position of the lower strip 50c illustrated in FIGS. 2 and 2A, and the operation will be exactly the same as previously described with respect to wiring two terminals on the lower strip 50c.

During the interconnection of a terminal on the upper terminal strip 50a by the left gun 185 and a terminal on the lower terminal strip 50c by the right gun 185, the cylinder 102 will not be energized to lower the mounting plate since one of the terminals to be connected is on the lower strip 50c. The pusher mechanism 281 will, however, subsequent to the advance of the left carriage 59 to a load position, be rendered effective once again to advance the bar 284 in a horizontal direction until precluded by positioning of the detent 296 within the last V-shaped notch 292 of the detent bar. The detent bar 284 is precluded from advancing beyond this last notch due to actuation of two microswitches. One of the microswitches, 400, is engaged by a switch actuator 402 while the other (not shown), which is positioned on the other side of the detent bar, is engaged by a switch actuator projecting from the opposite side of the bar 284 (inwardly from the plane of the drawing as viewed in FIG. 2). This additional horizontal movement (two notches) of the bar 284 adds to the horizontal movement imparted by the cam 149 to move the left carriage 59 and gun 185 to the right a distance equal to the needed length of the left leg of the U, which length is equal to the combined height of the strips 50c and 50b plus the distance up of the particular terminal on the upper strip 50a. For this reason, the distance between the notches 292-292 is set equal to the height of one plate to provide a coarse horizontal movement for the left gun 185 in the formation of the left leg of the U.

In this wiring situation, the fine and coarse elevators 136 and 137 are also operated to move the left gun 185 upward the same distance as the horizontal movement just described to form the left leg of the U and bring the left gun 185 into horizontal alignment with the terminal to be connected thereby.

Similarly, when the left gun interconnects a terminal on the middle terminal strip 50b to a terminal on the terminal strip 50c, the air cylinder 102 is inoperative and the second of the three notches 292 will be engaged by the detent 296. In this instance, the microswitch (not shown) positioned in alignment with the microswitch 400 but on the opposite side of the detent bar 284 will be engaged by a switch actuator 403.

To accomplish the connection of a segment of wire between a terminal on the lower terminal strip 50c with the left gun and a terminal on the upper terminal strip 50a which will have the right leg of the wire secured thereto, neither the cylinder 102 nor the pusher mechanism 281 will be rendered effective and the formation of the left leg of the U will be described with respect to the connection of the terminals on the lower strip 50c. How-

ever, the coarse air cylinder 156 on the right carriage 61 will be rendered effective to move the coarse elevator 137 up where the right welding gun 185 is in alignment with the terminal strip 50a. A prescribed rotation of the cam 147 will then operate the fine elevator 136 to bring the right gun 185 into horizontal alignment with the selected terminal on the upper strip 50a.

In the instance where it is desired that a terminal on the terminal strip 50b have the left leg of a segment of wire 51 secured thereto and right leg thereof secured to a terminal on the terminal strip 50a, the cylinder 102 will be operated to lower the mounting plate 89 one unit and the cylinder 156 will be rendered effective to elevate the right gun 185 one additional unit. Similarly, the interconnection of a terminal on the terminal strip 50a with the left gun and a terminal on the terminal strip 50b with the right gun will require the concomitant actuation of the cylinder 102 by one unit and the pusher mechanism 281 by one unit.

A more detailed description of the mode of operation will best be appreciated when considered in conjunction with the schematic illustrated in FIGS. 11-37. The system utilized to label the components to be hereinafter described consists of a series of four numerals. The first two numerals designating any component will refer to the figure number on which the element is located, the last two to the element or component itself. For example, a relay in FIG. 27 shall be designated 27--. The last two digits will be determined by the number of articles previously described in that particular figure. Consequently, the first article described in any figure shall be designated 2701, 3701, 1101, etc. and the second 2702, 3402, etc.

Referring now to FIG. 21, an auto-cycle start push button switch 2101 is shown which, when depressed, initiates a cycle of operation. The closure of switch 2101 provides ground at a junction 3501, thereby completing a path for energizing current from a 48-volt junction 2102 through relays 2103, 2104 and 3502. The energization of the relay 2103 results in the closure of contacts 2105 and 1501. Closure of the contact 1501 supplies 48 volts from a source 1502 through a normally closed contact 1503 of a relay 2106, the contact 1501 and a normally closed contact 1504 of a reset relay 1505 to a plurality of junctions 1506, 1507, 1508 and 1509. The 48 volts present at the junction 1509 is directly applied through a normally closed contact 1510 of a stop relay 1511 and a normally closed contact 1512 of an error relay 1513 to a clutch coil 2301 of the drive motor (not shown) for the tape reader 64.

Current flow from the junction 1509 through the clutch coil 2301 to a ground 2303 results in the initiation of operation of the tape reader 64 and more particularly in the actuation of a plurality of cams 2304. As the tape, a segment of which is illustrated in FIG. 42, is advanced through the tape reader, a plurality of pins 2305 under the control of the cams 2304 successively ascertain the perforations punched in each row. Upon sensing a hole or perforation, the pins 2305 cause the closure of an associated contact 2306, and in accordance therewith provide ground pulses to a plurality of junctions 2307, 2308, 2309, 2310, 2311 and 2312. The program from which the punched tape is derived utilizes six columns, the first five of which when perforated provide grounding pulses indicative of information which shall be later shunted to the various control units.

The five columns representing intelligence to be utilized directly by the various control units have been designated by the letters A, B, C, D, and E. A sixth column F is utilized solely within a check circuit which functions to indicate any inconsistencies which might inadvertently be present in the tape. This sixth or check column F when punched will present a grounding pulse to the junction 2312, whereas the columns A through E when punched will provide grounding pulses at the junctions

2311 to 2307, respectively. A ground pulse resulting from a perforation or punch in row 1, column A, will result in a ground pulse being presented at the junction 2311, a junction 2313 and in addition thereto a wiper arm 5 1101 of a rotary switch generally designated by the numeral 1102. It will be noted that the rotary switch 1102 comprises ten contacts 1103, each of which represents one of the ten rows on the tape. Similarly, ground pulses present at the junctions 2307 through 2310 will be selectively shunted to wiper arms (not shown) on rotary switches similar to 1102 that are represented by blocks 1301, 1302, 1303 and 1104, respectively.

Referring now to FIGS. 15 and 23, the function of the check circuit shall be described. Assuming that columns A, C and E of row 1 have been punched in accordance with a programmed mode of operation, ground pulses will be present at the junction 2311, the junction 2309 and the junction 2307. Similarly, ground pulses will appear at junctions 2313, 2314 and 2315, thereby providing a path for energizing current from a conductor 2316 which carries current from the junction 1508 through current-limiting devices 2317 and simultaneously through relays 2318, 2319 and 2320 to the grounded junctions 2321, 2322 and 2323. The energization of the relay 2318 will result in the closure of a contact 2324, while the energization of the relays 2319 and 2320 will result in the closure of contacts 2325 and 2326, respectively.

The concomitant closure of contacts 2325 and 2326 precludes relays 1514 and 1515 from being rendered effective by placing ground potential at junctions 1517 and 1518 as well as junctions 1519 and 1520. The absence of a difference of potential across the relays precludes the energization thereof. The closure of contact 2324 provides a path for energizing current to a relay 1521 that may be traced from the junction 1509 through a current-limiting device 1516, the relay 1521 and the contact 2324 to a junction 1522 which is at ground potential as a result of a ground pulse being supplied from the tape reader to a junction 2327. The energization of the relay 1521 results in the closure of a contact 1523 thereby shunting current flow from a junction 1508 around the error relay 1513 and through the contact 1523 to a junction 1524 which is connected to the grounded junction 2327 by a conductor 1525.

The nature of the checking circuit as previously described is that of an exclusive "or" circuit. Consistent with the programmed mode of operation, the check circuit insures that an odd number of punched holes are present in each and every row advanced through the tape reader 50. Accordingly, as information is received from the tape the check circuit will, upon ascertaining a satisfactory program, function to preclude the error relay 1513 from being energized. Should the tape be punched with an even number of holes in any single row, the relay 1521 as well as a relay 1526 are precluded from operation and neither the contact 1523 nor a contact 1527 will be closed to shunt the current around the error relay 1513. As a result, the error relay will be energized, drawing up the contact 1512 and thereby breaking the path for current flow from the 48-volt junction 1509 to the clutch coil 2301 of the tape reader 64.

Additionally, upon energization of the error relay 1513, contacts 1528 and 1529 will be drawn up, thereby locking the error relay in an energized state. Subsequent to a visual examination of the tape and a completion of the necessary corrections or modifications thereof, a reset push button 1530 may be depressed, thereby completing a path for energizing current from a 48-volt supply 1531 through the reset relay 1505 to the grounded junction 1532. Upon energization of the reset relay 1505, the contact 1504 will be opened, thereby removing 48 volts from the junction 1507 resulting in the deenergization of the error relay and the other instrumentalities within the circuit previously energized.

Referring again to FIG. 11 and more particularly to the

stepping switch 1102, it may be noted that when a ground pulse is relayed from the aforementioned junction 2315 to the wiper arm 1101, a path for energizing current for a relay 1105 is provided that may be traced from a conductor 1106 which is connected to the 48-volt junction 1507 through the relay to the now grounded contact 1103 which the wiper arm engages. The energization of the relay 1105 will result in the closure of a locking contact 1107 and a contact 1108. Similarly, the relays 1109, 1110, 1111, 1112, 1113, 1114, 1115, 1116 and 1117 will be energized and locked up if and when a ground pulse is supplied to the wiper arm when positioned in engagement with the contact 1103 associated with the particular relay. The necessity of the locking circuit is clear since each ground pulse is instantaneously applied and the control circuits which will ultimately receive information pulses from the relays 1105, 1109, etc. will not necessarily be immediately conditioned to utilize the information. This feature of the circuit is highly desirable since information may be fed through the tape reader at any time during the previous wiring operation and time does not become a critical factor in the read-in of information to the wiring machine.

The cyclic stepping of the wiper arm from the first contact 1103 to the tenth contact 1103 is under the control of a stepping relay 1533 which is rendered effective each time a ground pulse is provided to the junction 2327 from the tape reader thereby completing a path for current through the stepping relay from the 48-volt supply 1531. Just as the energization of the relay 1105 and, consequently, the closure of a contact 1108 results from presence of a punched hole in row 1, column A, a contact 1118 will be drawn up by a relay (not shown) if a ground pulse is provided thereto due to a punch being present in row 1, column B. Similarly, perforations existing in row 1, columns C, D and E will result in the closure of contacts 1304, 1305 and 1306.

Referring again to FIG. 42, the segment of tape illustrated therein is punched with a program representative of one cycle of operation. Since this program yields an odd number of punches in each row, column F will not be punched in order that the programmed mode of operation conform to the conditions which the testing circuit has been devised to check.

In accordance with the assumption that the segment of tape advanced through the tape reader for the present cycle of operation has punched therein the aforementioned program, the contacts 1204 to 1206 will be drawn up as a result of the energization and locking up of the relays 1115 to 1117 associated with the selector switch 1102. Similarly, contacts 1118, 1122 to 1124 and 1207 to 1211; contacts 1304, 1307, 1308, 1401 and 1402; contacts 1305, 1310, 1406 to 1408, 1410 and 1411; and contacts 1313, 1412 and 1414 will be drawn up by the energization of the relays associated with and represented by blocks 1104, 1303, 1302 and 1301, respectively. It should be noted that the remaining contacts will not be drawn up since the closure of these contacts would represent perforations or punches that are not present in the tape.

The energization and locking up of the relay 1115 and the drawing up of contact 1204 provides a ground at a normally open contact 1618. Accordingly, ground potential is present at the normally open contacts 1535 through 1537, 1540 to 1542, 1545, 1546, 1548, 1550, 1601, 1602 and 1604 to 1606, the closure of which is controlled by a transfer relay 1551. Similarly, contacts 1610 through 1612, 1614, 1618, 1619, 1621, 1623, 1624, 1626 and 1628 have ground potential applied thereto and are controlled by a transfer relay 1552.

Referring again to FIG. 35, it will be recalled that the depression of the auto-cycle start switch 2101 resulted in the energization of the relay 3502. When rendered effective, the relay 3502 effects the closure of contacts 3503, 3401, 3402, 3403, 3404, 3405 and 3201. The closure of the contact 3503 locks the relay 3502 in an energized state while the closure of contacts 3403 and 3404

initiates a sequence of returns of the four major components which comprise the carriages 59 and 61.

Closure of contact 3403 completes a path for energizing current to a relay 1801 that may be traced from a 48-volt source 1802 through a current-limiting resistor 1803, the relay 1801, the contact 3403 and a normally closed contact 2601 of a relay 2901 to a ground 2602. A path for current completed by the closure of the contact 3404 may be traced from the source 1802 through a current-limiting resistor 1804, a relay 1805 which is thereby energized, the contact 3404 and a normally closed contact 3406 of a relay 3601 to a ground 3407. The energization of the relay 1801 results in the closure of contacts 1806, 1901 and 1902 and the opening of contacts 1903 and 1904. The energization of the relay 1805 likewise results in the closure of contacts 1807, 1905 and 1906 and the opening of contacts 1907 and 1908. The simultaneous closure of the contacts 1806 and 1807 due to the energization of the relays 1801 and 1805 completes a circuit from a 48-volt source 2603 through each of the relays 1808 and 1809 to the grounded junctions 1810 and 1811 thereby resulting in the energization of these relays. The energized relay 1809 closes the contact 1909 while opening contacts 1910 and 1911. The relay 1808 causes the closure of a contact 1912 and the opening of contacts 1913 and 1914.

The function performed by the actuation of the contacts 1901 through 1910 inclusive is to reverse the polarity of the voltage supplied from a conductor 1915 to the armatures 1916 and 1917 of the right and left "Z" motors 308, which control the operation of the tool-mounting plates 186 and results in the return of these members in the reverse "Z" direction to a "clear" position. When the tool-mounting plates 186 for the right and left guns have been fully detracted, a pair of microswitches 197 are actuated thereby closing contacts 3701 and 3702 and completing paths for energizing current from a 48-volt supply 2902 through a conductor 2903, the relays 3601 and 2904 to ground through the contact 3701 and the relay 2901 to ground through the contact 3702. The energization of the relay 2901 results in the drawing up of contacts 2701 and 2702 and the opening of the contact 2601, thereby resulting in the deenergization of the relays 1801 and 1808. Similarly, the energization of the relay 3601 draws up contacts 3602, 3603, 3408, 3409 and 3203 and interrupts a path for current flow to the relays 1805 and 1809 by opening the contact 3406. The deenergization of the relays 1801 and 1805 and consequently 1808 and 1809 results in the removal of the reverse polarity from the armatures 1916 and 1917 of the "Z" control motors 308.

The energization of the relays 3601 and 2901 and the drawing up of contacts 3408 and 2702 completes a path for energizing current from the conductor 1915 to a current-limiting resistor 1918, a relay 1919, the contact 2702, the contact 3408 and the contact 3401 to a ground 3410. The energized relay 1919 performs a function identical to that of the previously described relay 1805; however, in this instance, it is the polarity of the voltage supplied to an armature 1920 of the "Y" fine motor 144 which is reversed. The motor 144 controls the fine positioning elevator 136 for the right carriage 61. In a similar manner and as a result of the closure of contacts 3409 and 2701, a relay 1921 is energized and accomplishes the reversal of the polarity applied to the armature 1922 of the D.C. motor 144 for the left fine positioning elevator 136 of the carriage 59. In accomplishing the reversal of the polarity applied to these armatures 1920 and 1922 from the conductor 1915, the relays 1919 and 1921 draw up contacts 1812 and 1813 to complete a path for energizing current to a pair of reversing relays 1814 and 1815.

The closing of the contact 3201 of the relay 3502, the contact 3203 of the relay 3601 and the contact 3202 of the relay 2901 completes a path for energizing current from a 48-volt D.C. source 3204 through a relay 3205 to a ground 3206. The energization of the relay 3205

results in the actuation of contacts 3207, 3208, 3209 and 3210 which function to remove the 48 volts from a commutator contactor assembly generally designated by the numeral 3211 supplied through the relays 3212 and 3213. A path for energizing current is completed to these relays from the source 3204 through the contacts 3207 and 3208 and a pair of normally closed reversing switches 3214 and 3215 to the ground 3206.

The energization of the relay 3213 results in the closure of a contact 3216. This completes a path for energizing current from the source 3204 through the contact 3216, the contact 3217, a relay 3219, the contact 3405, a drawn-up contact 3411 of the relay 2901 and a drawn-up contact 3412 of the relay 3601 to a ground 3413. The energization of the relay 3219 results in the drawing up of a contact 3220, thereby completing a path for current to a ground 3221 through the relay 3218. The energization of the relay 3218 results in the closure of contacts 3222 and 3223 while simultaneously opening the contact 3217 and the contact 3604.

Upon opening, the contact 3217 breaks the path for energizing current to the relay 3219 thereby resulting in the opening of the contact 3220. A path for current flow may be traced to a relay 3224 from a 48-volt junction 3225 through the contact 3223, the contact 3222 and a normally closed contact of a detent microswitch 3226 to a ground 3206. The energization of the relay 3224 results in the drawing up of a contact 3301 thereby completing a path to ground from a 90-volt source 3302 to a clutch coil 3304 which functions to return the carriages 59 and 61 to the load position. The return of the carriages under the control of the clutch 3304 is uninterrupted since the opening of the contact 3604 interrupted the path for current flow to a detent solenoid 2841 which had previously locked the carriages in alignment with the work-holding fixture.

The return of the "Y" fine elevators to a clear position and the carriages 59 and 61 to a load position occurs simultaneously with the actuation of a pair of "Y" coarse air valves 3605 and 3606 which results from the drawing up of the contacts 2107 and 2108 of the previously energized relay 2104. A plurality of microswitches are actuated when the various carriage motions previously described reach their clear or load positions. As the fine elevator on the left gun 59 returns to a down position, the contact 3607 is drawn up, completing a path for energizing current from a conductor 2800 through a relay 3608. Similarly, when the right fine elevator is returned to the down position, the contact 3609 is closed resulting in the energization of the relay 3610. The return of the "Y" right coarse and left coarse elevators to the down position results in the simultaneous energization of the relays 3611 and 3612 due to the closure of the contacts 3613 and 3614, respectively. When the carriages are advanced to the load position under the control of the coarse clutch 3304, a microswitch 110 is engaged resulting in the closure of a contact 3615 and the energization of an "X" coarse slow relay 3616. As the carriages are finally advanced to a load position, a stop microswitch 118 is engaged resulting in the closure of a contact 2802, thereby completing a path for current from the conductor 2800 through a relay 2803 to ground through the contact 2802.

The energization of the relays 3608, 3610, 3611 and 3612 results in the closure of contacts 3617, 3618, 3619 and 3620, respectively, while the energization of the relay 2803 results in the closure of a contact 2804, as well as contacts 2805, 2604 and 2720 and in addition thereto, opens contact 2806. As a result, a path for energizing current may be traced from a source 2109 through a relay 2110, the contact 2804, the contacts 3618, 3617 and 3602, a drawn-up contact 3621 of the relay 2901 and the contacts 3619 and 3620 to ground through a normally open contact 1553 of the stop relay 1511. Closure of the contact 1553 will occur simultaneously with the drawing

up of contacts 1554 and 1555 and the opening of the contact 1510 of one segment of the tape which results from ten actuations of the stepping relay 1533 and the positioning of the wiper arm 1556 at a contact 1557 on a stepping switch generally designated by the numeral 1558. Energizing current for the stop relay 1511 upon the advance of the wiper arm 1556 to the contact 1557 may be traced to the junction from the 48-volt junction 1506 through the contact 1528, the relay 1511, the wiper arm 1556 and a diode 1559 to the grounded junction 1524.

The energization of the relay 2110 results in the closure of a contact 2111 and the opening of a contact 2112. The opening of the contact 2112 results in the deenergization of the relays 3502 and 2104, thereby rendering the instrumentalities previously energized during the return of the carriages ineffective. The closed contact 2111 provides a path for current that may be traced from a junction 2807 on the conductor 2800 through a normally closed contact 2808 of a relay 2605 and the contact 2111 to a junction 2113, at which point parallel paths for energizing current are provided through the relays 2114 and 2809 to a junction 2115. Thereafter, current flow may be traced from the junction 2115 through a diode 2116 and the drawn-up contact 2105 of the relay 2103 to a ground 2117.

Upon being energized, the relay 2114 draws up contacts 2118, 2001, 1816, 1701 and 1560. The contact 2118, when closed, completes a locking circuit for the relays 2114 and 2809. The closing of the contact 1560 completes a path for current flow from the 48-volt junction 1506 through the transfer relays 1551 and 1552 to a ground 1561. Upon closing, contact 1701 provides ground potential at a junction 1702, thereby supplying ground to the "Z" positioning primary storage relays 1703 to 1706, the "Y" fine positioning primary storage relays 1629, 1630 and 1707 to 1712 and the "Y" coarse primary storage relays 1561, 1562, 1630 and 1631. Drawn-up contact 1816 similarly provides a ground for the primary storage memory relays 2328 to 2337 and 3101 to 3103 which control the wire-drawing operation of the carriages 59 and 61 and also supplies ground to the secondary storage memory relays 2501 to 2509 and 3305 to 3308. The ground supplied by the closed contacts 1701 and 1816 to the control relays of the aforementioned units maintains these relays in an energized state until a welding operation has been completed. The original energization of these relays however results from the drawing up of contacts associated with the transfer relays 1551 and 1552 which have ground pulses supplied thereto in conformity with the programmed segment of tape previously read into the tape reader 64.

The energization of the relay 2809 results in the drawing up of contacts 2905, 2810 to 2812, 2703, 2510 and 2401. In addition thereto, the relay 2809 opens the contact 2906. The closure of the contact 2510 completes a circuit from the source 3204 through relay 3226 to ground and results in the energization of the relay and the drawing up of a contact 3309. The contact 3309 completes a circuit to ground from the source 3227 through a clutch coil 3228 that functions to control the "X" fine motor 68.

Associated with the clutch coil 3228 is a brake coil 3229 and a relay 3230. The clutch and brake system comprising the coils 3228 and 3229 is selectively rendered effective by the opening and closing of a pair of contacts 2511 and 2512 under the control of a relay 2402. The relay 2402 controls the clutch and brake simultaneously so that at any given time either the clutch or the brake is energized. For example, the brake is connected to the cam shaft 77 and precludes the rotation thereof when the clutch is deenergized. This system makes it possible to use a relatively inexpensive drive motor for the "X" fine cam 75 but more important it relieves the braking device of having to contend with motor armature inertia.

Subsequent to the initiation of the "X" fine positioning

controls due to the energization of the "X" fine clutch coil 3228 and after the "X" fine system has positioned the cam 75 in the desired position, a coincidence circuit identical to that described in the copending application of E. N. Lenk, J. G. Weeks and Q. W. Wiest, Serial No. 753,703, filed August 7, 1958, will be rendered effective to provide energizing current to the relay 2402 thereby precluding the motor 68 from further operation. A plurality of resistors, diodes and relay contacts, the latter being under the control of the primary storage memory relays previously described, comprise the aforementioned coincidence circuit generally designated by the numeral 2403.

A plurality of contactor arms 2404 which engage the code disc 326 ascertain conducting and non-conducting segments 2405 on the disc and, in accordance with predetermined specifications, the desired positioning of the "X" fine cam. The desired position having been attained, a signal is produced which is fed to the grid 2406 of a vacuum tube 2407, the output of which is supplied to the grid 2408 of an amplifier 2409. The amplified signal, indicating that the coincidence has occurred and the desired position of the "X" fine cam has been reached, is in turn supplied to the grid 2410 of a thyratron 2411. The firing of the thyratron 2411 results in the energization of the relay 2402 which, as previously described, results in the actuation of the contacts 2511 and 2512. Upon being energized, the relay 2402 will break a path for current through the clutch coil 3228 while the contact 2512 being drawn up energizes the brake coil 3229.

Drawn-up contacts 2810, 2811 and 2812 complete circuits from one side of an A.C. source 3001 represented by a conductor 2813 through the solenoids 2814, 2815 and 2816 to the other side of the source 3001 represented by a conductor 2817. The energization of the solenoid 2814 actuates the left gun terminal-gripping member 234 while the solenoids 2815 and 2816, when energized, accomplish the release of the right and left gun gripping jaws 233. The actuation of the left gun terminal-gripping member 234 by the energization of the solenoid 2814 is necessitated due to space limitations that would preclude the advance of the left gun into engagement with wire emanating from the cutter-stripper apparatus 258.

A solenoid 2818 which controls the operation of the right gun terminal-gripping member 234 need not be actuated since space limitations are not critical during the advance of and the gripping of the wire by the right gun. A contact 3002 which is opened by the energization of the relay 2809 interrupts a path for energizing current from a junction 3003 through a cutter stripper clearance position solenoid 3004 to a junction 3005 secured to the opposite side of the A.C. source 3001. The deenergization of the solenoid 3004 results in the advance of the cutter-stripper apparatus 258 to a wire pick-up position.

The drawing up of a contact 2905 as a result of the energization of the relay 2809 completes a path for energizing current from the source 2603 through the relay 1809, the contact 2905, a normally closed contact 2119 of a relay 2201 and a normally closed contact 2120 of the microswitch 202 to a ground 2121. The energization of the relay 1809 supplies voltage of proper polarity to the armature 1916 of the motor 308. Consequently, the right gun is advanced in the "Z" direction until brought into engagement with microswitch 202 thereby opening the normally closed contact 2120 resulting in the deenergization of the relay 1809 and the stopping of the advance of the right gun in the load position. Closure of the normally open contact 2122 completes a path for energizing current from the 48-volt junction 2123 to a relay 2124 to the ground 2121. The energization of the relay 2124 results in the drawing up of contacts 2125 and 2202 and the opening of a contact 2203. The closure of the contact 2125 locks up the relay 2124 while the simultaneous closing and opening of the con-

tacts 2202 and 2203 initiates a time-delay circuit for the relay 2201 that comprises, among other things, a vacuum tube 2204.

When the vacuum tube 2204 begins conducting, the relay 2201 is energized thereby drawing up the contacts 2205 and 2126 while opening contacts 2002, 2119 and 2206. The functions previously performed by the simultaneous closing and opening of the contacts 2202 and 2203 for the time-delay circuit comprising the vacuum tube 2204 is repeated by the contacts 2205 and 2206 which initiate a time-delay circuit comprising a vacuum tube 2207 for a relay 2208. The opening of the contact 2002, as a result of the energization of the relay 2201, interrupts current flow to the right gun wire-release solenoid 2815 thereby allowing a spring (not shown) to close the wire-gripping jaws 233.

The energization of the relay 2208, when the vacuum tube 2207 begins conducting, accomplishes the closure of contacts 2127 and 2128. The closure of the contact 2128 completes a path for energizing current to the cutter stripper left wire-gripping jaw solenoid 3007 that may be traced from a conductor 3006 through the contact 2128 and a normally closed contact 2907 of a relay 2908 to a junction 2909 on the conductor 3005 which is secured to the opposite side of the A.C. source 3001. The energization of the solenoid 3007 results in the release of the wire 52 emanating from the supply spool 251 and permits the wire to be withdrawn therefrom.

The closing of the contact 2127 as a result of the energization of the relay 2208 provides a path for energizing current to ground through the relay 2106 and results in the closing of contacts 2129, 1817 and 1818 and the opening of contacts 1564 and 1503. The opening of contact 1564 results in the deenergization of the transfer relays 1551 and 1552 and, consequently, the opening of the contacts controlled thereby. This operation results in the removal of the information previously supplied by the transfer relays 1551 and 1552 due to the drawing up of contact 1560. Upon opening, the contact 1503 removes 48 volts from the tape-intelligence distributor which comprises, among other things, the checking circuit and the stepping switches 1102, 1104, 1301, 1302 and 1303 and results in the deenergization of the relays associated therewith and conditions these units for reading the next block of intelligence for a subsequent cycle of operation supplied by the tape reader.

The closure of the contact 1817 results in the initial positioning of the right gun carriage 61 to the preliminary wire-drawing position under the control of the "X" coarse system in accordance with information supplied by the memory relays 2328 to 2337 and 3101 to 3103, inclusive. A commutator 3231 utilized by the "X" coarse control system consists of fifteen brass segments 3232, each of which is two inches in length and positively insulated to preclude any electrical interconnection therebetween except as directed by the relays 2336, 2337, 3101 and 3102. The commutator contactor assembly 3211 comprises three contacts 3233 which are spaced at one-inch intervals thus allowing for the travel of 29 inches of the right gun carriage relative to the detent bar 113.

Information supplied from the relays 2336, 2337, 3101 and 3102 in the form of contact closures associated therewith may be utilized to advance the carriage in one-inch intervals and preclude the advance thereof positively and accurately. A relay 3103, the energization of which is controlled by a punch in row 1, column E, or the least significant digit of the "X" coarse positioning information, controls the operation of a plurality of contacts 3234. The state of these contacts 3234 determines which pair of contacts 3233 are to be used to search the commutator segments 3232 for discontinuity.

The desired position for the right gun carriage under the control of the "X" coarse control unit may be an even or odd integral distance; nonetheless, two of the three contactors 3233 will be used in ascertaining this

position. The leading contactor of the two shall be utilized to provide a slow or warning signal upon reaching the first discontinuity thereby slowing the "X" coarse drive motor during the last inch of travel of the carriage relative to the detent bar. The second of the two contactors provides a stop signal and precludes the "X" coarse motor from further operation. As previously described, motion is imparted to the carriage 61 upon energization of the clutch coil 3304 as a result of the closure of the contact 3301 under the control of the relay 3224. The relays 3218 and 3219, which condition the relay 3224 for operation, are provided with energizing current upon the drawing up of the contact 1817 as a result of the energization of the relay 2106. The relay 3218, it will be recalled, not only conditions the relay 3224 for operation but also functions to preclude the detent solenoid 2801 from holding the carriages at the load position. Consequently, both of the detents 116 and 111 will be fully withdrawn due to the functioning of the cylinders 117 and 108.

The remaining contacts 2129 and 1818, which were drawn up by the energization of the relay 2106, complete paths for energizing current to relays 2130 and 2131, respectively. Current for the relay 2130 may be traced from the junction 2132 through the relay to a normally closed contact 2906 of the relay 2704 and the contact 2129 to a ground 2133. A contact 2134 which is closed upon energization of the relay 2130 completes a path for energizing current from one side of the A.C. source 3001 through a "Y" left coarse pusher detent solenoid 3003, a normally closed contact 3009 of a relay 2910 and a contact 2134 to the conductor 3005 which emanates from the opposite side of the A.C. source. A contact 2135 which is simultaneously opened due to the energization of the relay 2130, interrupts a path for current flow to a normally energized pusher retract solenoid 3010. The concomitant energization and deenergization of the solenoids 3008 and 3010, respectively, accomplishes the advance of the left carriage 59 in the "X" direction from its clearance location to a wire pick-up position.

Energizing circuits completed by contacts 2136, 2137, 2138 and 2139 that are drawn up when the relay 2131 is rendered operable initiate the vertical advance of the fine and coarse elevators 136 and 137 of the right gun 61 and condition the relay 2911 for operation. The upward advance of the coarse elevator 137 is accomplished through the energization of a solenoid 3622 associated with the Electro-aire valve 151 of the right gun carriage. Energizing current for the solenoid 3622 may be traced from one side of a transformer 1923 through a junction 3623, the solenoid 3622, a normally closed contact 3624 of the "X" coarse slow relay 3616, a drawn-up contact 3625 of the relay 3612, the contact 2136 of the relay 2131 and either contact 1924 or 1925 drawn up by the energization of the "Y" coarse positioning primary storage relays 1561 and 1562 to the other side of the transformer 1923.

The upward advance of the "Y" fine elevator of the right gun carriage 61 is accomplished through operation of the motor 144 as a result of the application of positive potential to the armature 1920. The closure of the contact 2137 provides ground to a commutator contactor 1819 through the normally closed contact 3626 of the "X" coarse slow relay which has been deenergized by the further horizontal advance of the right gun carriage 61. The contact 1819 which is of the carbon-brush type may be selectively advanced relative to four segments 1820 which comprise the commutator disc generally designated by the numeral 1821.

In accordance with the previous assumption that information pulses were provided to accomplish the energization of the right "Y" fine positioning relays 1630 and 1708 for the right fine elevator, the contacts 1821 and 1824 associated therewith will be drawn up. The closure of contacts 1821 and 1824 will complete para-

lal paths for energizing current from the segments 1820 which represents the binary digits 1 and 8 through the right carriage "Y" fine motor-control relay 1814 to a 48-volt source 1824. Since the series combination of a brush and control relay contact for each of the segments is ultimately secured in parallel through the motor-operate relay, and since only one grounded commutator brush is provided, the ground to the relay 1814 will be provided by the most significant digit with which the contact 1819 is brought into engagement. Nonetheless, the energization of the relay 1814 results in the closure of a contact 1926 which completes a path for energizing current from a 48-volt junction 1927 through a normally closed contact 1928 of the relay 1919, the contact 1926, the armature 1920 of the motor 144 and through a contact 1929 of the relay 1919 to a ground 1930. The cam 147 and the commutator 146 are mounted on the same shaft and, consequently, upon actuation of the motor 144 will rotate in the same direction until such time as the desired position has been attained.

The closure of the contact 2139 associated with the relay 2131 completes a path for energizing current that may be traced from the junction 2807 through the contact 2808, the contact 2111, the junction 2113, the junction 2819, a relay 2911 and the contact 2139 to a ground 2140. A time-delay circuit comprising a capacitor 2705 which shunts the relay 2911 and insures that the coarse elevator 137 of the right carriage 61 has reached its desired position before the energization of the relay 2911 occurs.

The energization of the relay 2911 results in the drawing up of a contact 2820 and the opening of a contact 2606. The contact 2606, upon opening, interrupts a path for energizing current to the relay 3219, thereby removing the starting pulse from the "X" coarse control motor clutch 3304. The drawn-up contact 2820 completes a path for energizing current through a relay 3504 that may be traced from a 48-volt junction 2706 through the relay 3504, current-limiting resistor 3505, the contact 2820, normally closed contact 2821 of a relay 2707, the contact 2003 of the relay 1814, a contact 3627 of the relay 3213 and a contact 3628 of the relay 3230 to a ground 3629. In order that energizing current be provided for the relay 3504, however, the contacts 2003 and 3627 must be closed. Accordingly, the advance of the right carriage fine elevator 136 must be completed so that the relay 1814 is deenergized; the right carriage under the control of the coarse system must be positioned at the desired wire-drawing location so that the relay 3213 is deenergized; and the rotation of the "X" fine cam under the control of the motor 67 must be completed so that the relay 3230 is energized.

Upon being rendered effective, the relay 3504 draws up contacts 3506, 3507, 3703 and 3310 while opening contact 3414. The closure of the contact 3506 locks the relay 3504 in an energized state through a resistor 3505. The closing of the contact 3507 completes a path for energizing current from the junction 2819 through a relay 2822 to a ground 3508. Drawn-up contact 3703 completes a path for energizing current from the conductor 3006 through a solenoid 3011, the contact 3703, and the contact 2907 of the relay 2908 to the junction 2909. Upon being energized, the solenoid 3011 activates the air cylinder 270 thereby closing the right wire-gripping jaws 261 of the cutter-stripper mechanism 258.

The opening of the contact 3414 results in the deenergization of the relay 2131 and the opening of contacts 2136 to 2139. Upon closing, the contact 3310 completes a path for current from a 48-volt source 3104 to a junction 3311 and thereafter through a relay 3312 to a ground 3313. The energization of the relay 3312 results in the closure of contact 3314 thereby providing energizing current to a relay 3315. A contact 3316 is also closed due to the energization of the relay 3312 and contact 3105 is opened, the latter resulting in the deenergiza-

tion of relays 2328 through 2337 and 3101 to 3103, thereby removing information for the wire-drawing operation previously stored therein.

Closure of the contact 3316 in conjunction with the energization of relay 3315 and the drawing up of contacts 3317, 3235 to 3245 and 3106 to 3108 accomplishes the transfer of information for the final weld positioning of the carriage from the secondary storage memory relays to the primary memory relays within the control unit. The relay 2822, energized by the closure of the contact 3507, draws up contacts 2823 and 3012. The closure of the contact 3012 completes a path for current from the A.C. source 3001 to the cutter-stripper wire severing solenoid 3013 and results in the energization thereof. A relay 2824 that is energized by the closure of the contact 2823 draws up a contact 2825, thereby resulting in the energization of a relay 2826, and simultaneously completes a path for energizing current from the source 3001 to a wire-strip solenoid 3014 by drawing up a contact 3015. With the right carriage and associated gun located at the wire-drawing position, the concomitant operation of the instrumentalities under the control of the solenoids 3013 and 3014 prepares the left end of the wire for withdrawal from the cutter-stripper mechanism.

A contact 2912 that is closed by the energization of the relay 2826 completes a path for energizing current from the source 2603 through the left gun-mounting plate motor control relay 1808, a normally closed contact 2913 of the relay 2908 and a normally closed Microswitch contact 2142 to the ground 2121. The energization of the relay 1808 as previously described results in the actuation of the contacts 1912 and 1913, the selective opening and closing of which completes a path for current to the armature 1917 of the gun-mounting plate motor thereby initiating the advance of the left gun in the "Z" direction to the wire pick-up position. When the left gun has been fully advanced and the pick-up position has been attained thereby, the Microswitch 2142 is operated resulting in the deenergization of the relay 1808 and the energization of the relay 2908.

The energized relay 2908 opens contacts 2907, 2913 and 2827 and closes contacts 2828 and 2914. Contact 2827, upon opening, interrupts the circuit for the previously energized left gun wire-release solenoid 2816 thereby permitting the jaws to close and grip the cut and stripped left end of the wire to be joined to a selected terminal 51. Upon opening, the contact 2907 simultaneously deenergizes the left and right wire-jaw solenoids 3007 and 3011. Consequently, the left wire-gripping jaws 259 of the cutter-stripper mechanism 258, which were previously held open by the solenoid 3007, will be closed and the right wire-gripping jaws 261, previously held closed by the energized solenoid 3011, will be opened. The relay 2908 which is locked in an energized state by the closure of the contact 2914 associated therewith completes a path for energizing current to a relay 2829 by drawing up the contact 2828. A path for current to the relay 2829 may be traced from the junction 2113 through the contact 2828 to ground at a junction 2830.

Relay 2829, when energized, closes contacts 2708, 2915 and 3016. The closure of the contact 3016 results in the reenergization of the cutter-stripper clear position solenoid 3004 completing a path for current from the junction 3003 to the conductor 3005. The solenoid 3004, when energized, initiates the withdrawal of the cutter-stripper mechanism 258 to a clearance position.

Contact 2708, when closed, completes a path for current flow from the junction 2819 through a time-delay relay 2709, the contact 2708 and a current-limiting resistor 2710 to a grounded junction 2711. The time-delay relay 2709 will not be immediately energized, however, and the time-delay characteristics thereof are such that a sufficient interval of time will elapse to allow the cutter-stripper mechanism to be fully withdrawn to the clear-

ance position. When energized, the relay 2709 draws up contacts 2831 and 2832 and opens the contact 3017. The contact 3017, when opened, interrupts the energizing circuit for the wire-strip solenoid 3014 thereby stripping the end of the wire emanating from the supply spool, which wire end will be gripped by the right gun during the next cycle of operation.

Closure of the contact 2831 completes a path for energizing current that may be traced from the junction 2819 through a relay 2143, the contact 2831, and a normally closed contact 2833 of the relay 2704 to a grounded junction 2834. A path for current to a time-delay relay 2835 is provided by the closure of the contact 2832 and may be traced from the junction 2819 through the relay 2835, the contact 2832 and a current-limiting resistor 2836 to a grounded junction 2837.

The time-delay characteristics of the relay 2835 preclude the energization thereof until the coarse and fine "Y" positioning of the left gun initiated by the energization of the relay 2143 has been consummated. Upon being energized, the relay 2143 draws up contacts 2145, 2146 and 2147. A function identical to that performed by the relay 2131 is accomplished by the relay 2143. More particularly, the contact 2147 when closed completes a path for energizing current to a solenoid 2630 that controls the operation of the Electro-aire valve 151 for the coarse elevator 137 of the left gun carriage 59. The contact 2146, closed as a result of the energization of the relay 2143, supplies ground to the commutator 1825 through the contactor 1826. The ground provided to the segments of the commutator 1825 by the contactor accomplishes the energization of the relay 1815 and, as a result, the passage of current through the armature 1922 of the left fine elevator drive motor 144.

This combined horizontal and vertical movements of both the right and left gun accomplishes the formation of the U-shaped segment of wire due to the action of the mandrels 212. The energization of the relay 2835 subsequent to the completion of the vertical advance of the coarse and fine elevators of the left gun results in the closure of a contact 2916 and the opening of a contact 3018. Upon opening, the contact 3018 deenergizes the wire-cut solenoid 3013 thereby allowing the wire-cutting jaws 262 to be opened prior to a subsequent cycle of operation. The contact 2916 completes a path for energizing current to a relay 2917 that may be traced from the junction 2819 to a junction 2918 and thereafter through the relay 2917, the contact 2916 and a normally closed contact 2148 of the motor-control relay 1815 to the ground 2121. The contact 2148 is closed since the relay 1815 was deenergized by the completion of the advance of the "Y" fine elevator of the left-gun carriage to its programmed height.

The contact 2145 of the relay 2143, when closed due to the energization of the latter, completes a path for energizing current from the junction 2819 through relay 2143 and a diode 2149 to a ground 2150. The energization of the relay 2148 results in the drawing up of contacts 1565 and 2151 and results in the opening of a contact 2004. The closure of the contact 2151 locks the relay 2148 in an energized state while the opening of the contact 2004 opens the energizing circuit of the left gun terminal grip solenoid 2814 thereby opening the terminal-gripping jaws on the left gun.

The energization of the relay 2917 results in the closure of contacts 2712 and 2838. Contact 2712, when closed, completes a path for energizing current from a 48-volt junction 2713 through the relay 2707 and the contact 2712 to a ground 2714. The contact 2838 which is drawn up simultaneously with the contact 2712 completes a circuit from a junction 2839 that is connected to one side of the A.C. source 3001 through a tow bar grip solenoid 2840 for the left carriage 59, the contact 2838 and a normally closed contact 2005 of a relay 2152 to the conductor 3005 which emanates from the other

side of the A.C. source. The energization of the solenoid 2840 results in the closing of the jaws 126 on the tow bar 106 thereby securing the left carriage rigidly to the right carriage 61 for movement therewith.

The energization of the relay 2707 results in the opening of contacts 2414 and 2821 and the drawing up of a contact 2715. Contact 2715, when closed, completes a path to ground for energizing current emanating from the junction 2819 through a current-limiting resistor 2716, the relay 2704 and the contact 2715. The contact 2412, when opened, removes the plate circuit supply voltage from the tube 2411 within the "X" fine coincidence circuit 2403 thereby resulting in the deenergization of the relay 2402. The de-energization of the relay 2402 as previously described results in the opening of the contact 2512 and the closure of contact 2511 thereby opening the circuit to the "X" fine brake coil 3229 and the relay 3230 while at the same time providing energizing current for the "X" fine clutch coil 3228. The deenergization of the relay 3230 results in the opening of a contact 3631 and consequently in the deenergization of the solenoid 3704 which retracts the detent bar to clear the "X" fine cam 75 during the rotation of the latter to the programmed position.

The energization of the relay 2704 as a result of the closure of the contact 2715 results in the opening of the contacts 2906 and 2837 and the closure of contacts 2717, 2718, 2413 and 2607. The closure of contact 2413 restores plate voltage to the vacuum tube 2411 and as a result, when coincidence is ascertained by the circuit 2403, the relay 2402 is again energized and the cam 75 is precluded from further rotation by the reenergization of the brake coil 3229.

The opening of the contact 2906 results in the de-energization of the relay 2130 previously energized by the closure of the contact 2129 under the control of the relay 2106. Upon being deenergized, the relay 2130 opens a contact 2134 thereby interrupting a path for current flow to the previously energized pusher-detent solenoid 3003. The return of the contact 2135 to a normally closed position due to the deenergization of the relay 2130 completes a path for energizing current to the pusher-retract solenoid 3010.

Closure of the contact 2607 associated with the relay 2704 applies a ground pulse to the starting network for the "X" coarse control system thereby initiating the horizontal advance of the interlocked carriages to the final or weld position. The contact 2718 locks the relay 2704 in an energized state while the contact 2717, when closed, conditions a relay 1931 for energization. The relay 1931 will not be energized until the "X" coarse and "X" fine motions imparted to the interlocked carriages 59 and 61 have been completed. An interlocked circuit associated with the relay 1931 insures the completion of this horizontal motion of the carriages and completes a path for energizing current to the relay thereby resulting in the closure of contacts 1932, 1827 and 2006. Contacts 1932 and 1827, upon closing, complete a path to ground for energizing current from the source 2603 through the relays 1808 and 1809 thereby initiating the inward advance or "Z" motion of the gun-mounting plates 186 of the right and left carriages 59 and 61.

The contact 2006 conditions a relay 2007 for energization by completing a path to ground from the relay through the now drawn-up contacts 1911 and 1914 of the relays 1809 and 1808. This interlocking circuit precludes the energization of the relay 2007 until the programmed position for the guns has been reached and the relays 1808 and 1809 have again been deenergized. Thereafter the relay 2007 will be rendered effective opening contacts 1828 and 1933 and closing contacts 2008 and 2009. The contacts 1828 and 1933 function to interrupt the path for current flow from the source 2603 to ground through the relays 1808 and 1809. These relays, although previously deenergized, are thereby positively precluded

from any further energization until a welding operation has been completed.

The closure of the contact 2008 locks the relay 2007 in an energized state, while the contact 2009 provides ground for an automatic welding cycle control circuit generally designated by the numeral 2010. The application of ground to the welding cycle control circuit results initially in the energization of a relay 2011 thereby drawing up contacts 2012 and 2013 while opening contacts 2014, 2015 and 2016. The closure of the contact 2013 completes a path for current flow from one side of an A.C. source 2017 through a normally closed contact 2018 of a relay 2019, the contact 2013 and simultaneously through the paralleled left and right terminal-gripping solenoids 2814 and 2818 to the other side of the A.C. source. The opening of the contact 2014 removes a short from a capacitor 2020 in the grid circuit of the vacuum tube 2021 allowing the capacitor to begin charging to a predetermined voltage at a rate determined by a variable resistor 2022. Similarly, the contacts 2015 and 2016, when opened, remove shorts that previously shunted capacitors 2023 and 2024, respectively.

When the capacitor 2020 has charged to a sufficient potential and the vacuum tube 2021 begins conducting, a path for energizing current is completed to a relay 2025 thereby resulting in the closure of a contact 2026 and the opening of contacts 2027 and 2028. Closure of the contact 2026 initiates the charging of the capacitor 2023 in the grid circuit of a vacuum tube 2029. The energization of the relay 2025 further results in the completion of the weld operation due to the opening of the contacts 2027 and 2028. These contacts, when open, interrupt the energizing circuits for a pair of solenoids 2030 and 2031. The deenergization of the solenoids 2030 and 2031 results in the contraction of a pair of spring devices (not shown) that function to advance the wire-gripping jaws of the right and left welding guns 185 into percussive welding engagement with the terminals.

The vacuum tube 2029, when rendered effective by the build up of sufficient potential on the capacitor 2043, provides energizing current for the relay 2019 and results in the closure of a contact 2032 and the opening of the normally closed contact 2018. The contact 2032, when closed, initiates a timing circuit comprising the capacitor 2024 and a variable resistor 2033 that controls the firing characteristic of a vacuum tube 2034 and consequently the energization of a relay 2036.

A contact 2035 that is drawn up by the energization of the relay 2019 completes a path for energizing current to the solenoids 2815 and 2816, the energization of which results in the wire-gripping jaws of the right and left welding guns 185 being opened. The contact 2018 on the other hand interrupts the path for energizing current previously applied to the terminal-grip solenoids 2814 and 2818. The energization and deenergization of the aforementioned solenoids having been completed, sufficient time will have elapsed so that the vacuum tube 2034 will be in a conducting state and the relay 2036 will be energized. The energization of the relay 2036 indicates that the welding operation has been completed and by drawing up contacts 1829 and 1830, this relay provides energizing current for the control motors 308 of the gun-mounting plates which, when activated, return the guns to a clear position.

Upon retraction of the right and left welding guns to a clear position, a circuit is completed to energize the relay 2152. The energization of the relay 2152 results in the drawing up of contacts 2154 and 2155 and the opening of contacts 2005. The closure of contact 2154 results in the reenergization of the relays 2104 and 3502, which again function to direct the various components on the carriages to return to the load position as previously described. The closure of the contact 2155 will, in conjunction with other components within an interlocking circuit, provide a path for energizing current to the

relay 2719 upon closure of the contact 2720. The contact 2720 will close when the right and left carriages have returned to the load position and the "X" coarse stop relay 2803 has been energized.

As outlined in the previous general description of the mode of operation, numerous programs may be devised for the automatic wiring machine. Many such programs will require the selective actuation of the mounting plate height control cylinder 102 to index the bottom of the terminal strips successively into alignment with a datum or reference plane defined by the position of the tools when the vertical elevators are inoperative and/or the further advance of the pusher mechanism 281 subsequent to the advance of the left carriage from a clear to a load position. Wiring programs might further require that each of these devices be rendered effective and in addition thereto, upon the completion of all the desired wiring operations, the cylinder 93 be conditioned for operation to rotate the entire mounting plate. When successive wiring operations demand the actuation of these various instrumentalities, the operation thereof will be controlled by the relays 2611, 2612, 2616, 2617 and 2618. Relays 2612 and 2617, when provided with ground pulses from the contacts associated with the transfer relays, will control the operation of the pusher mechanism 281. The relays 2611 and 2616 will similarly dictate during what portions of the cycle of operation the cylinder 102 will be rendered effective to selectively raise and lower the mounting plate. The actuation of the cylinder 92 and consequently the rotation of the mounting plate is under the control of the relay 2618.

Should a programmed mode of operation be introduced to the automatic wiring machine that requires identical wiring operations on each of the several terminal strips 50a, 50b and 50c, the relay 2719 will, upon being energized, accomplish these identical wiring operations. When energized, the relay 2719 draws up contacts 2608, 2609 and 2610 and connects the mounting plate height control relays 2611 and 2612 to the stepping switch device generally designated by the numeral 2613. The function of the stepping-switch device 2613 is to selectively control the lowering and raising of the mounting plate as well as the rotation thereof when these identical wiring operations are to be performed.

The foregoing description is illustrative of but one cycle of operation of the automatic welding machine. Any number of programs may be devised for the machine and in accordance therewith, the previously described instrumentalities will or will not be selectively operated to accomplish the result desired by the programmer. In general, however, reference to FIGS. 39 and 40, which are indicative of the sequence of operation of these various instrumentalities and the relative time relation for the operation of each, will provide a rapid means for ascertaining which of the components will be rendered effective during any particular cycle of operation and, furthermore, will indicate the increment of time necessary for the operation thereof.

It is to be understood that the above-described arrangements are simply illustrative of the application of this invention. Numerous other arrangements may be readily devised by those skilled in the art which will embody the principles of the invention and fall within the spirit and scope thereof.

What is claimed is:

1. In an automatic wiring apparatus, a control unit including a source of intelligence pulses, a support frame, a carriage movably mounted within said support frame, a wire working tool mounted on said carriage for movement in three directions of a three dimensional coordinate system, means for advancing wire to a load position, a work holding fixture, and means rendered effective in accordance with output from said intelligence source for selectively advancing said wire working tool through said three dimensional coordinate system to align wire fed

from said wire advancing means with said work holding fixture.

5 2. In an automatic wiring device, a source of intelligence pulses, a housing, a pair of carriages movably mounted within said housing, a selectively operable tool mounted on each of said carriages, a work holding fixture, a first means rendered effective by intelligence pulses from said source for selectively controlling the advance of said tools and said carriages in a horizontal direction, 10 a second means rendered operable by additional intelligence pulses from said source for selectively controlling the advance of said tools and said carriages in a vertical direction, and a third means controlled by said intelligence source for advancing said tools with respect to said carriages in a direction perpendicular to said horizontal and vertical movements thereof and into alignment with said work holding fixture.

15 3. An automatic machine for connecting a wire between a pair of spaced terminals, which comprises a first 20 wire-gripping means, a second wire-gripping means, a supply of wire having a free end, means for actuating said first wire-gripping means to grip the end of the wire emanating from said supply, means for moving said first gripping means a first predetermined distance, means for severing said wire, means rendered effective by the operation of said severing means for actuating said second gripping means to grip the wire, means for locking said first and second gripping means together, means for moving said locked first and second gripping means a second 25 predetermined distance to present the gripped ends of the wire to said terminals, and means for attaching said ends of the wire to the terminals.

30 4. In an automatic wiring apparatus, a wire feed means, means for selectively severing wire emanating from said 35 wire feed means, a first and a second carriage positioned in alignment with said wire feed means, a wire-gripping means secured to said first carriage, a first motor driven means for actuating said wire gripping means to grip the end of wire emanating from said wire feed means, a rack and pinion means for advancing said first carriage a predetermined distance in a horizontal direction; a wire-gripping means mounted on said second carriage, means for rendering said wire severing means effective, and means rendered operable by the actuation of said wire severing means for rendering said wire-gripping means mounted on said second carriage effective.

45 5. In a machine for accomplishing the percussive welding of wires to selected terminals, a support frame, a work-holding fixture mounted on said support frame at one extremity thereof and having a plurality of terminal strips secured therein, a carriage mounted on said support frame for movement relative thereto, said carriage comprising a base plate, a fine elevator, a coarse elevator and a tool-mounting plate, a supply of wire positioned at the other extremity of said support frame, a welding tool secured to said tool-mounting plate for movement therewith, means for advancing said welding tool into gripping engagement with an end of the wire emanating from said supply, means for imparting horizontal motion to said carriage thereby advancing said carriage from a position in alignment with said supply into a position in alignment with said work-holding fixture, means for accomplishing the vertical advance of said coarse elevator to position the welding tool in alignment with one of said terminal strips, drive means associated with said fine elevator for advancing said tool into alignment with a selected terminal on said strip, and means for advancing said tool relative to said coarse and fine elevators to bring the wire gripped therein into percussive welding engagement with said terminal.

60 6. In an automatic wiring machine, a source of intelligence pulses, a support frame, a wire feed device situated at one extremity of said frame, a drive means, a first carriage movably mounted on said frame in alignment with said wire feed device and controlled by said

drive means, a second carriage mounted for movement relative to said frame, a work holding fixture positioned at one extremity of said frame, means for selectively shunting a portion of said intelligence pulses to said drive means to control the advance of said first carriage from said wire feed device to said work holding fixture, and means for utilizing a further portion of said intelligence pulses to control the advance of said second carriage in accordance with the advance of said first carriage.

7. In an automatic wiring machine, a support frame, a plurality of guide rods secured to said support frame, a pair of carriages movably mounted on said guide rods at one extremity of said support frame, a movably mounted work holding fixture positioned at the opposite extremity of said support frame, a wiring tool mounted on each of said carriages, drive means for advancing a first of said carriages into alignment with said work holding fixture, a tow bar secured to said first carriage for movement therewith, and means mounted on the other of said carriages for gripping said tow bar so as to interlock said first and said second carriages.

8. In an automatic wiring device, a support frame, a work holding fixture positioned at one extremity of said support frame, a wire feed device positioned at the opposite extremity of said support frame, a pair of carriages movably mounted within said frame in alignment with said wire feed device, a wire working tool mounted on each of said carriages, a source of intelligence pulses, means for advancing the wire working tool mounted on a first of said carriages into position to receive wire from said wire feed device, means controlled by the output of said intelligence source for advancing said first carriage from said wire receiving position into a position in alignment with said work holding fixture, a tow bar secured to said first carriage, and means mounted on said second carriage for gripping said tow bar to allow said second carriage to advance in accordance with the movement of said first carriage.

9. A machine for selectively interconnecting a pair of spaced terminals of a terminal strip, which comprises a pair of carriages, a wire-working tool mounted on each of said carriages, said wire-working tools each having a pair of gripping jaws associated therewith, a support frame whereon said carriages are movably mounted, a work-holding fixture positioned at one extremity of said support frame and having a terminal strip secured therein, a supply of wire having a free end, means for advancing a first of said wire-working tools into gripping engagement with the free end of the wire emanating from said supply, means for imparting horizontal and vertical motion to said first wire-working tool to withdraw a length of wire from said supply, means for advancing the second of said wire-working tools into gripping engagement with the opposite extremity of the length of wire withdrawn by the first of said wire-working tools, means for imparting vertical movement to the second of said wire-working tools, a tow bar secured to and projecting outwardly from a first of said carriages, gripping means associated with a second of said carriages, means for rendering said gripping means effective to grip said tow bar thereby interlocking said first and said second carriages, means for simultaneously advancing said carriages horizontally into alignment with a pair of selected terminals on said work-holding fixture, and means for causing said wire-working tools to join the portions of the wire held by the jaws thereof to the selected terminals.

10. In an automatic wiring machine, a support frame, a supply of wire mounted at one extremity of said support frame, a carriage positioned in spaced relationship to said supply of wire and mounted on said support frame for movement relative thereto, said carriage comprising a base plate, a coarse vertical positioning elevator, a fine vertical positioning elevator and a tool-mounting plate, a wire-working tool mounted on said tool-mounting plate, drive means for advancing said wire-

working tool into gripping engagement with the end of the wire emanating from said source, a rack secured to and projecting outwardly from the base plate, a pinion rotatably mounted within said support frame in engagement with said rack, an elongated detent bar, selectively operable means for rotating said pinion to drive said rack and said carriage associated therewith relative to said detent bar, a wedge-shaped detent secured to the underside of said carriage, and means for selectively advancing said detent into engagement with said detent bar upon the advance of said carriage to a first predetermined position under the control of said selectively operable means.

11. An automatic wiring machine, which comprises a support frame, a wire-feed device mounted at one extremity of said support frame, a carriage positioned in spaced relationship to said wire-feed device and mounted on said support frame for movement relative thereto, said carriage comprising a base plate, a coarse vertical positioning elevator, a fine vertical positioning elevator and a tool-mounting plate, a wire-working tool mounted on said tool-mounting plate, drive means for advancing said wire-working tool into gripping engagement with an end of the wire emanating from said wire-feed device, a coarse positioning device comprising a rack secured to and projecting outwardly from the base plate of said carriage and a pinion rotatably mounted within said support frame in engagement with said rack, an elongated detent bar, selectively operable means for rotating said pinion to drive said rack and said carriage associated therewith relative to said detent bar, a fine positioning device comprising a cam rotatably mounted in said support frame, drive means for selectively rotating said cam, a wedge-shaped detent secured to the underside of said carriage, means for selectively advancing said detent into engagement with said detent bar upon the advance of said carriage to a first predetermined position under the control of said selectively operable means, and means rendered effective upon the advance of said detent into engagement with said detent bar and the rotation of said cam to a preconcerted position to advance said detent bar into positive engagement with said cam.

12. An automatic wiring machine for making a succession of connections between selected pairs of terminals on any of a plurality of terminal strips mounted one above the other on a work holder, which comprises means for moving said work holder vertically through a predetermined distance in units equal to the height of one terminal strip so as to bring the bottom of the lowest terminal strip involved in each successive wiring operation into a fixed horizontal datum plane, means including a pair of movable wire-gripping members for forming a succession of lengths of wire designed to reach between the selected pair of terminals in each operation, means for moving the wire-gripping members along selected paths above the datum plane so as to present the ends of the wire lengths to the selected pair of terminals to be connected in each operation when the bottom of the lowest terminal strip involved in each operation lies in the datum plane, means for joining the ends of the wire lengths to the selected pair of terminals, and programming means for sequentially operating the foregoing means in a preselected succession of wiring operations.

13. In a machine for accomplishing successive wiring operations on selected pairs of terminals projecting from a plurality of terminal strips in accordance with a programmed mode of operation, a support frame, a mounting plate for said terminal strips positioned at one extremity of said support frame, a source of intelligence pulses, means controlled by a portion of the output of said source for selectively raising and lowering said mounting plate thereby defining a first vertical plane through which said mounting plate advances, a pair of wire working tools mounted within said support frame for selective movement in a horizontal plane, a second vertical plane parallel to said first vertical plane defined

by the lowering and raising of said mounting plate and a plane normal to said horizontal plane and said second vertical plane, said horizontal plane defining a reference level wherat said wire working tools and the bottom of the lowermost terminal strip secured within said mounting plate are initially positioned, drive means controlled by a further portion of the output of said source for directing the advance of each of said wire working tools in said horizontal plane, means controlled by still a further portion of output of said source of intelligence pulses for advancing said tools in said second vertical plane and said normal plane relative to said reference level to accomplish wiring operations on terminals projecting from terminal strips positioned substantially above the lowermost terminal strip, means rendered operable by further portions of output of said source during successive cycles of operation for selectively lowering terminal strips through said first vertical plane into alignment with said wire working tools, means for rotating said mounting plate within said support frame, and means controlled by the final output of said source of intelligence pulses for rotating said mounting plate and said terminal strips positioned therein upon completion of a predetermined number of wiring operations.

14. Apparatus for interconnecting a selected pair of horizontally spaced terminals of a terminal array including several rows of terminals having several terminals in each row, which comprises means including a pair of wire-gripping members for fashioning a length of connecting wire into a U-shape having a base equal in length to the horizontal distance between the selected pair of terminals to be connected and having legs equal in length to the distances of the selected pair of terminals above a common datum plane below the lowest terminal to be connected, means operable after the formation of the U-shaped connecting wire for moving the wire-gripping members into proximity with the terminals to be connected, and means for joining the wire held by the gripping members to the selected pair of terminals.

15. Apparatus for making a programmed succession of connections between selected pairs of horizontally spaced terminals of a terminal array including several rows of terminals having several terminals in each row, which comprises means including a pair of wire-gripping members for fashioning a succession of lengths of connecting wire into a succession of U-shapes having bases equal in length to the horizontal distance between the selected terminals to be connected in each operation and having legs equal in length to the distances of the selected terminals above a common datum plane below the lowest terminal to be connected in each operation, means operable after each formation of a U-shaped connecting wire for moving the wire-gripping members into proximity with the terminals to be connected in that operation, means for joining the wire held by the gripping members to the selected terminals, and programming means for causing sequential operation of the foregoing means in a succession of wiring operations in accordance with the positions of the terminals to be connected according to a predetermined pattern of operation.

16. Apparatus for forming a wire into a U-shape having a base and legs of predetermined variable lengths not necessarily equal to each other, which comprises a right and a lefthand carriage mounted for horizontal movement, a mandrel mounted on each carriage, an elevator member carried by each carriage for vertical movement with respect thereto, a wire-gripping member mounted on each elevator member, a supply of wire having a free end and positioned to the left of said carriages, means for operating the righthand wire-gripping member to grip the end of the wire, means for moving said righthand carriage to the right through a distance equal to the desired length of the base of the U plus the length of the lefthand leg thereof, means for moving the righthand elevator upward through a distance equal to the desired length of the righthand leg of the U, these two

movements combining to move said righthand gripping member upward and away from said wire supply so as to withdraw from said wire supply a length of wire equal to the perimeter of the U, said righthand gripping member and the righthand mandrel being so arranged with respect to each other that the upward movement of that gripping member serves to bend the wire 90° around that mandrel so as to form the righthand leg of the U, means for cutting the withdrawn length of wire to provide a second free end therealong, means for operating the lefthand wire-gripping member to grip the second free end on the wire, means for moving said lefthand carriage to the right through a distance equal to the desired length of the lefthand leg of the U, and means for moving the lefthand elevator upward through a distance equal to the desired length of the lefthand leg of the U, these last two movements combining to move said lefthand gripping member upward and to the right, said lefthand gripping member and the lefthand mandrel being so arranged with respect to each other that the upward movement of that gripping member serves to bend the wire 90° around that mandrel so as to form the lefthand leg and base of the U.

17. Apparatus for interconnecting a selected pair of horizontally spaced terminals of a terminal array including several rows of terminals having several terminals in each row, which comprises a right and a lefthand carriage mounted for horizontal movement, a mandrel mounted on each carriage, an elevator member carried by each carriage for vertical movement with respect thereto, a wire-gripping member mounted on each elevator member, a supply of wire having a free end positioned to the left of said carriages, means for operating the righthand wire-gripping member to grip the end of the wire, means for moving said righthand carriage to the right through a distance equal to a horizontal distance A between the selected terminals to be connected plus a height B of a lefthand one of the terminals above a common datum plane below the lowest terminal to be connected, means for moving the righthand elevator upward through a distance equal to a height C of the righthand terminal above the datum plane, these two movements combining to move said righthand gripping member upward and away from said wire supply so as to withdraw from said wire supply a length of wire equal in length to $A+B+C$, said righthand gripping member and the righthand mandrel being so arranged with respect to each other that the upward movement of that gripping member serves to bend the wire 90° around that mandrel, means for cutting the withdrawn length of wire to provide a second free end therealong, means for moving said lefthand carriage to the right through a distance equal to the length B, means for moving the lefthand elevator upward through a distance equal to the length B, these last two movements combining to move the lefthand gripping member upward and to the right, said lefthand gripping member and the lefthand mandrel being so arranged with respect to each other that the upward movement of that gripping member serves to bend the wire 90° around that mandrel, the foregoing movements co-operating to fashion a U-shaped length of connecting wire having a base of length A, a lefthand leg of length B and a righthand leg of length C, means operable after the formation of the U-shaped connecting wire for moving said wire-gripping members into proximity with the terminals to be connected, and means for joining the ends of the U-shaped connecting wire held by the gripping members to the selected terminals.

18. The apparatus as defined in claim 17, wherein the gripping members comprise wire-working tools having normally open wire-gripping jaws, wherein means are provided for moving said tools on the elevators of the carriages in a direction Z perpendicular to a direction X of movement of the carriages and a direction Y of

movement of the elevators, wherein means are provided for moving said tools first predetermined distances in the Z direction so that the jaws thereof surround the wire, wherein means are operated after such movement in the Z direction for closing the jaws to grip the wire, wherein the movement of the wire-gripping members into proximity with the terminals includes the further movement of said tools in the Z direction, and wherein means are provided for disengaging the wire from the mandrels during the further movement of said tools in the Z direction.

19. The apparatus as defined in claim 18, wherein the jaws of the wire gripping tools are originally aligned horizontally in the datum plane and are moved upward during the formation of the U-shaped connecting wire into the horizontal planes of the respective terminals to be connected, wherein means are provided for locking the two carriages together for constrained movement in the X direction after the formation of the U-shaped connecting wire, and wherein the movement of the wire-gripping members into proximity with the selected terminals to be connected is accomplished first by means for moving the locked carriages in the X direction into alignment with the terminals, followed by the further movement of the tools in the Z direction.

20. The apparatus as defined in claim 17, wherein the terminals to be connected may occur in any of several terminal strips having several rows of terminals each and mounted one on top of the other on a work holder, a datum plane being defined near the bottom of each terminal strip, wherein means are provided for moving the work holder vertically, and wherein means are provided for operating said work holder moving means according to a predetermined pattern of operation such that the datum plane of the lowest terminal strip involved in any

particular wiring operation is brought into the horizontal plane of the wire-gripping members prior to the operation of the gripping members to form the U-shaped length of wire.

5. 21. The apparatus as defined in claim 20, wherein coarse and fine drive means are provided for the vertical movement of the righthand elevator, the coarse drive means being operable to move the elevator member upward in units equal to the height of one full terminal strip and being operated only when the righthand terminal to be connected is located on a terminal strip above the lowest terminal strip involved in the operation as governed by the work holder moving means, the fine drive means being operable each time to elevate the righthand gripping member a distance corresponding to the height of the selected terminal above the datum plane for the particular terminal strip involved, and wherein coarse and fine drive means are provided for both the horizontal movement of the lefthand carriage and the vertical movement of the lefthand elevator, the coarse drive means operating to impart motion in units equal to the height of one terminal strip and being operated only when the lefthand terminal is located on a terminal strip above the lowest terminal strip involved in the operation, the fine drive means being operable each time in accordance with the height of the selected terminal above the datum plane for the terminal strip involved.
